CLAIM

The ornamental design for an object gripper, as shown and described.

DESCRIPTION

FIG. 1 is a front, left perspective view for an object gripper; FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom thereof.

The broken lines depict features of the object gripper that form no part of the claimed design.

1 Claim, 4 Drawing Sheets
